Fig. 5

FIGURE 1 is a front elevational view showing the shelf of the instant design;

FIGURE 2 is a rear elevational view showing the instant shelf;

FIGURE 3 is a top plan view of the instant shelf;

FIGURE 4 is a bottom plan view of the shelf; and

FIGURE 5 is a side elevation view of the shelf, both sides being alike.

The characteristic features of my design reside in the combination of the spaced shelf members each such member having a spirally twisted strip on the forward edge thereof and in association with the peripheral scroll-like ornaments wherein two of such ornaments are spaced in face to face relationship at the top of the shelf to produce a heart-shaped effect as shown.

I claim:

The ornamental design for a wall shelf, as shown and described.
